[57] **CLAIM**

The ornamental design for a plasma cutting-welding torch head, as shown.

DESCRIPTION

FIG. 1 is a perspective view looking at the front and one side of the cutting-welding torch head;

FIG. 2 is a side elevation of the cutting-welding torch head, looking at the opposite side of that shown in FIG. 1;

FIG. 3 is a front elevation thereof;

FIG. 4 is a rear elevation thereof.

FIG. 1

FIG. 2

FIG. 3

FIG. 4
